Primary Examiner — Brett Miller*Assistant Examiner* — Rani J Abdallah(74) *Attorney, Agent, or Firm* — Shuttleworth & Ingersoll, PLC; Timothy J. Klima(57) **CLAIM**

The ornamental design for a liquid container, as shown and described.

DESCRIPTION

FIG. 1 is a front perspective view of a liquid container;

FIG. 2 is a front view thereof;

FIG. 3 is a right side view thereof;

FIG. 4 is a left side view thereof;

FIG. 5 a rear side view thereof;

FIG. 6 is a top view thereof; and,

FIG. 7 is a bottom view thereof.

The broken lines in the figures illustrate portions of the liquid container that form no part of the claimed design.

1 Claim, 7 Drawing Sheets(56)
